Primary Examiner — Jeffrey D Asch*Assistant Examiner* — Tracey J Bell(74) *Attorney, Agent, or Firm* — Amster, Rothstein & Ebenstein LLP(57) **CLAIM**

The ornamental design for a glove back, as shown and described.

DESCRIPTION

The FIGURE is a top view of a glove back showing our new design.

The portion(s) of the glove back shown in broken lines, which includes separate finger portions, are for environmental purposes only and do not form part of the claimed design.

1 Claim, 1 Drawing Sheet(56)
